UNITED STATES PATENT OFFICE.

EDWIN BALL STIMPSON, OF BROOKLYN, NEW YORK.

TAB-CUTTING MACHINE.

SPECIFICATION forming part of Letters Patent No. 703,748, dated July 1, 1902.

Application filed April 12, 1902. Serial No. 102,599. (No model.)

To all whom it may concern:

Be it known that I, EDWIN BALL STIMPSON, a citizen of the United States, residing in the borough of Brooklyn, county of Kings, and city and State of New York, have invented certain Improvements in Tab-Cutting Machines, of which the following is a specification.

This invention relates to what is known in the trade as a "tab-cutter." In a machine of this class as ordinarily constructed there is a bed on which the card to be cut is supported, a fixed shear-blade on said bed, a movable blade mounted to play in guides perpendicular to the fixed blade, means for operating the movable blade, a fixed back stop or gage for the card disposed parallel to the blade to limit the width or dimensions of the card, and an adjustable end stop or gage up to which the card is placed. In such a tab-cutter the blades, both fixed and movable, are so shaped as to leave on the edge of the card when cut or trimmed one or more projections called "tabs," which are usually of a semicircular form. Such cards are used in card-indexes and the like. These machines are found to be slow in operation by reason of the difficulty in conveniently and quickly removing the card after it is cut or trimmed, owing to the back-stop, which rises above the surface of the bed and the card, being fixed in position, and one of the important features of my invention is an automatic means for dropping or displacing this back-stop at the proper time, so as to leave the trimmed card free to be slipped off from the bed.

Another feature of the invention relates to means for coupling up the tab-cutter with the reciprocating head of a gang-punch and for securing the bed of the cutter in the slotted bed of said punch.

In the accompanying drawings, which illustrate an embodiment of the invention, Figure 1 is a plan of the tab-cutter detached. Fig. 2 is a front elevation of same. Figs. 3 and 4 are end elevations of the same, the former showing the parts in their normal positions and the latter showing them in the positions they occupy when the blade is depressed. Fig. 5 is a front view, on a smaller scale, showing the cutter mounted on a gang punching-machine; and Fig. 6 is a transverse ver-

tical section at line x^6 in Fig. 5. Figs. 7 and 8 illustrate a slight modification.

The tab-cutter comprises in itself the following features: 1 is the metal frame, on which is secured the bed 2, which supports the card and the fixed blade 3. The movable blade 3^a is secured to a slide 4, which plays in guides 5 on the base in a plane perpendicular to the surface of the bed. On the bed is mounted an adjustable end stop or gage 6 for the card (C in Fig. 1) to be cut or trimmed.

The back-stop 7, which has heretofore been fixed to the bed 2 so as to extend a little above the upper surface of the latter and take behind the card to be cut, is in the present construction coupled at each extremity to one arm of an elbow-lever 8^a, fulcrumed at 9 on the upright guide 5 on the base, the other or upright arm 8^b of the lever being coupled by a spring 10 to some part of the guide 5. The spring 10 keeps the arm 8^b of the lever up against a roller-stud 11 on the end of the slide 4, said roller projecting through and playing in a slot or aperture 12 in the guide 5. When the slide 4 and blade 3 are elevated, as in Fig. 3, the elbow-levers will be in such positions that they hold the back-stop 7 in its elevated and operative position; but when the slide and blade move down in cutting the roller-studs 11 wipe over cam-faces 13 on the upright arms 8^b of the elbow-levers, rock the levers, and depress the back-stop 7, as seen in Fig. 4. When the stop 7 is depressed to its full extent, a gravity-latch 14 engages a stud 15 on the lever-arm 8^b and holds the lever against return until the latch is lifted. This release is effected by the return movement of the slide 4, which causes the stud 11 to take under the latch and lift it out of engagement.

It will be noted that when the parts are at rest with the slide 4 elevated the upright arm 8^b of the lever bears against the stud 11 as a stop, and the said stud upholds the latch 14. It is not essential, however, that the roller-stud be used as a limiting-stop for the lever 8. Any form of stop may be employed for this purpose.

The operation is as follows: The card to be cut is placed with one end up to the gage 6 and with its rear edge up to the elevated back-stop 7. The blade 3^a now descends and shears

off the card; but in its descent the roller-studs 11 act through the elbow-levers to press down the back-stop 7 until its upper edge is below the card, so that the latter may be conveniently slipped back off from the supporting-bed. The latches 14 by locking the levers prevent the return of the back-stop to its normal position until the blade 3^a shall have nearly reached its normal elevation, when the 10 roller-studs take under the latches and displace them, thus leaving the springs 10 free to restore the parts again.

Figs. 5 and 6 show a gang punching-machine adapted for operating the cutter above 15 described. This machine is in most respects similar to or like that illustrated and described in my United States Patent No. 665,702, dated January 8, 1901, and hence will require only a brief description.

16 is the slotted bed of the punching-machine. 17 represents the upright guides for the vertically-reciproating head 18, and 19 represents the rods which operate the head. I have not deemed it necessary to show the crank-shaft, below which operate the rods 19, as this is fully illustrated in my said patent.

The base 1 of the cutter is supported on the bed 16 of the punching-machine, and it has on it blocks 20, which take in the slot 21 in 30 the bed 16, the cutter being thus made adjustable along said slot as a guideway.

On the upper edge of the slide 4 of the cutter are stems 22, adapted to engage adjustable holders 23 on the head 18. These holders 35 23 are substantially the same as those in the punch-holders described in my said patent—that is to say, each comprises a block mounted in a guideway in the head 18, which extends across the machine from side to side, 40 and a recessed holder mounted in a dovetail groove or way in said block, the said groove extending from front to rear of the machine. The stems 22 have heads which enter the recesses in the faces of the respective holders, 45 and thus couple the slide 4 to the head 18, so that the reciprocating movements of the latter are imparted to the slide.

It now remains to explain the means employed for locking the bed of the cutter in its 50 place in the slot in the bed 16. The blocks 20, which may form an integral part of the base 1, are made to fit rather loosely in the slot 21, and each is provided with an expanding and locking device. (Seen best in Figs. 2 55 and 3.) This device comprises a locking-plate 24, which may close into a recess formed in one face of the block 20, that is adjacent to a wall of the slot 21. This plate 24 has a stem 25, which extends into a hole or bore 26 in the 60 block 20 and which has a recess in its side so formed as to provide an inclined shoulder 27. A conical-pointed screw 28 is driven through the block 20 and impinges on said shoulder 27 in such a way as to drive out the locking-plate 24 in the manner of a wedge—that is to say, the screw drives or moves out the locking-plate in a direction at right angles to the

path of the screw. When the cutter is placed on the bed of the punching-machine and the blocks 20 made to engage the slot 21 therein, 70 the plates 24 will be in flush. The cutter is moved along the slot to the desired position and the screws 28 driven in forcibly, so as to set the locking-plates firmly against the wall of the slot 21. This will hold the cutter firmly. 75 The holders 23 are now moved into position and made to engage or embrace the stems 22, as seen in Figs. 5 and 6, and the cutter is ready for operation.

The slide 4 may have cushion-springs 29 in 80 the guides at its ends, and the end stop 6 may play in a slot or guideway 30 in the bed 2 and be held in position when set by a pin in its bottom engaging one of a series of holes 31 in the bed at the bottom of said slot 30, as 85 seen in Fig. 1.

This invention is not restricted in all respects to the specific construction herein shown. This construction may obviously be varied without departing materially from the 90 invention. One block 20, with its locking devices, would serve, but two are preferred.

Fig. 7 is a sectional view, and Fig. 8 a plan, illustrating a form of the displaceable back-stop. In this construction the stop 7^a is a rod 95 with a flat face 7^b and rotatively mounted in bearings on the bed 2, one of said bearings being seen at 32 in Fig. 8. On the respective ends of the rocking stop 7^a are cranks 33, to which are coupled the elbow-levers 8^a. Normally the face 7^b of the stop is in a vertical plane; but the lever 8^a rocks the stop so as to turn said face into a horizontal position level with the surface of the bed, or nearly so. Any similar form of displaceable stop may be 105 employed. Figs. 7 and 8 are fragmentary and only show the devices at one end of the stop.

It should be understood that the back-stop is not only movable and displaceable, but is 110 wholly displaceable, so as to permit the sheet to be slipped back off from the surface of the bed after it is cut. In fact, when cutting the usual stiff tab-cards singly in the ordinary way the latter will usually spring back beyond the edge of the bed when freed by the cutting-blade, at which time the back-stop will have been displaced, so as to be entirely out of the way.

Having thus described my invention, I 120 claim—

1. A cutter for the purpose specified, having a bed to support the sheet to be cut, a movable cutting-blade, a movable back stop or gage for the sheet, means for operating the 125 said cutting-blade, and means between the cutting-blade and back-stop which wholly displaces the latter when said blade makes its cutting movement, whereby the operator may remove the sheet by sliding it back off from the bed.

2. A cutter for the purpose specified, having a bed to support the sheet to be cut, a movable cutting-blade, a movable back stop

or gage for the sheet, means for operating the said cutting-blade and back-stop substantially simultaneously, whereby the back-stop is wholly displaced when the blade makes its operative movement so that the sheet may be slipped back off the bed, means for detaining the displaced stop during a part of the retracting movement of the blade, and means for returning the stop to its normal position when released.

3. A cutter for the purpose specified, having a bed to support the sheet to be cut, a slide and its guides, a cutting-blade carried by said slide, a fixed blade on the bed, a movable back-stop for the sheet, mechanism between the said stop and slide whereby the former is actuated by the latter, said mechanism comprising the elbow-levers carrying the back-stop and studs on the slide adapted to actuate or rock said levers when the slide makes an operative movement, the retracting-springs of the levers, the locking-latches adapted to be upheld normally by said studs, and the studs in the levers for said latches to engage.

4. The combination with a slotted bed to receive the cutter, of the said cutter having a block 20 on and extending below its base to engage said slot, the locking-plate 24, provided with a stem 25 guided in a bore in the

block, and a cone-pointed screw 28 driven in the block at an angle to the said stem and adapted to bear on a shoulder on the latter for moving out the clamping-plate into forcible contact with the wall of said slot, whereby the cutter may be moved along the slot in the bed and clamped at any desired point by means carried with the cutter.

5. The combination with the machine having a sliding head 18, a slotted bed 16, and holders 23 adjustably mounted on said head 18, of a cutter having a blade-carrying slide 4, provided with headed stems 22 to engage the holders 23, and means for locking the base of the cutter in the slotted bed 16, substantially as set forth.

6. A tab-cutter having a displaceable back-stop, a movable cutting-blade, and means between said blade and stop whereby the former wholly displaces the latter in its cutting movement, whereby space is provided for sliding the cut sheet back off from the bed.

In witness whereof I have hereunto signed my name, this 10th day of April, 1902, in the presence of two subscribing witnesses.

EDWIN BALL STIMPSON.
